UNITED STATES PATENT OFFICE.

CHESTER LEWIS, OF HAZARD, KENTUCKY.

AUTOMATIC MINE PUMP.

Application filed December 30, 1922. Serial No. 609,974.

To all whom it may concern:

Be it known that I, CHESTER LEWIS, a citizen of the United States, residing at Hazard, in the county of Perry and State of Kentucky, have invented certain new and useful Improvements in Automatic Mine Pumps, of which the following is a specification.

The invention relates to pumping devices particularly designed for removing the water which collects in mines or the like and which ordinarily has to be pumped out by hand. The present invention makes the use of pump men unnecessary and effects a labor saving of thousands of dollars annually in every mine in which it is employed.

More particularly stated, the objects of the invention are to automatically start the pump when the water in the mine has reached a predetermined level and to automatically cut off the power from the pump when the hole has been pumped dry. A further object is to automatically close the end of a suction pipe extending into the water hole when the water has been pumped dry, in order to keep out the air and also to hold back the water in the pipe, thus keeping the pump always primed.

Another object is to provide an improved form of switch for opening and closing the power circuit which operates the pump.

Other objects will appear hereinafter.

Illustrative embodiments of the invention are shown in the accompanying drawings in which:

Figure 1 is a side view of the switch and suction valve, and the operating mechanism therefor, some parts being shown in section,

Fig. 2 is a front view of the operating mechanism,

Fig. 3 is a view taken in line 3—3, of Fig. 1,

Fig. 4 is a side view similar to Fig. 1 showing a switch operating mechanism designed for use outside the mine,

Fig. 5 is a detail perspective view of that part of the switch operating mechanism which is common to the constructions shown in both Figs. 1 and 4,

Fig. 6 is a top view of the perforated water containing cup which serves to throw the switch in the construction shown in Fig. 4,

Fig. 7 is a detail on line 7—7 of Fig. 1,

Fig. 8 is a diagrammatic representation of a complete pumping system, Fig. 9 is a top plan view of a multiple switch designed for use with alternating current, Fig. 10 is a detail of the contact portion of the switch and is common to both the single and multiple switches,

Fig. 11 is a detail of a protecting screen used to keep out foreign material from the suction valve shown in Fig. 1. Referring to the drawings the numeral 1 designates a reducing coupling which is designed to be connected to the end of a pipe leading to a sump hole such as frequently found in old mines. On the end of the coupling 1 is secured a sleeve 2 into which

is screwed a second reducing coupling 1^a. A pipe nipple 3, threaded at each end is screwed into the coupling 1^a, the end which extends into the sleeve 2 being carefully ground to serve as a valve seat, and preferably galvanized to prevent rusting. The numeral 4 denotes a valve of any suitable construction, adapted to fit against the ground end of the nipple 3. As shown the valve 4 is provided with a plurality of legs 6, which extend into the sleeve 2 to prevent swaying of the valve, and to guide the same during its opening and closing movements. The legs 6 are preferably made of brass or other material which does not readily corrode.

Hingedly secured to the valve 4 is a rod 7 which extends through the nipple 3 and is secured at its other end to the lower end of a vertical lever 8 which is shown as pivoted on a rod 11 secured to a washer 9 which is screwed upon the end of the nipple 3.

Preferably the washer 9 is provided with a peripheral groove, which permits of a wire being drawn about the washer to hold a protecting screen 10 in position. The screen 10 is composed of wire of fine mesh, and is designed to be slipped over the washer 9 to prevent foreign substances which may be present in the water in the pump hole from entering the nipple 3 and clogging the valve 4. The screen may then be fastened on by drawing a wire tightly around the same at the groove in the washer.

The opening in the washer for passing the nipple 3 is preferably located below the center of the washer 9 to make room for the attachment of a lever 11 which is fixedly

secured to the front face of the washer. The screen 10 is preferably slotted at its upper portion to pass the lever 8 thus enabling it to be readily attached or removed at will without removing the lever 8.

The lever 8 is preferably forked at its upper end and is secured to a rod 12 having an elongated slot at the end where it is engaged by the forked portion of the lever 8, 10 thus enabling the latter to be pulled rearwardly by a coil spring 13 which is employed for the purpose of closing the valve 4. As shown, the spring 13 is secured at one end to the lever 8 at the other end to a 15 vertical extension 14 of a loop or band which passes about the sleeve 2 and is preferably secured thereto by means of a bolt to which the spring 13 may be attached.

The rod 12, to which the lever 8 is attached is shown as hinged at its opposite end to a bell crank 15 which is preferably journalled in the upper end of the vertical extension 14 of the loop. The bell crank 15 is preferably provided with a semicircular 25 extension having a plurality of apertures therein by means of which the bell crank is adjustably secured to an arm 16, which is hinged at one end to the vertical extension 14 and carries a float 20 at its opposite end. This construction enables the arm to be adjusted to any desired position for use in a perpendicular or horizontal water hole.

The arm 16 may be made extensible to any 35 desired length by the attachment of extension rod 17 which slips through a slot or loop on the end of rod 16 and is fastened by means of a band 18 provided preferably with a set screw for tightening the same in 40 adjusted position.

At a suitable position upon the extension 45 17 is secured a weight 19 which may be bolted thereto at any desired distance from its end, a plurality of bolt holes being provided for this purpose. Near the end of the float arm is secured the float 20 which may be made of any suitable non-corrosive material as galvanized sheet metal or brass. The float 20 as shown in Fig. 1 is of globular 50 shape, is hollow and air tight, and is provided with a loop or eye for bolting it upon the end of the float arm.

The float arm 16 is connected midway of its ends to the lower end of a lever 21. As 55 clearly shown in Fig. 7 the lever 21 is reduced at its lower end and is provided with a base or bracket to which the reduced position is secured by means of a nut threaded upon the end thereof. This bracket is provided with a threaded connecting bolt extending laterally therefrom, and designed to be secured in anyone of a plurality of eyes formed in the flat rod 16.

The lever 21 is preferably made in two 65 pieces thus making it adjustable, the lower

end of the upper portion 22 sliding through a slot or loop on the upper end of the lower member and being fastened by means of a band and screw at the desired position.

The upper end of the member 22 is forked 70 as at 22^a and is suitably attached to a crank 23. As shown the forked portions are provided with elongated slots which permit limited vertical movement relative to the ends of the crank arm 23. The crank may 75 be provided with rollers 24, one at each side, where the crank passes through the slots in the forks. The rollers are flanged at each end, the forks of the lever 22 fitting 80 inside the flanges, thus holding the crank 23 steady.

A coil spring 25 normally holds the fork 85 in tension against the crank 23, and is shown as attached at one end to the latter by means of a suitable bearing. The opposite end of the spring 25 is attached to a bracket 26 which is adjustably secured by means of a bolt to one of the forks of the member 22.

As most clearly shown in Fig. 3, the 90 bracket 26 has in addition to the arm to which the spring 25 is attached, a second arm parallel thereto, to which is secured a vertical fork 26^a having a loop 27 formed integral therewith, the spring 25 passing through and being guided within the loop, 95 as shown in Figs. 2 and 5. It will be noted that the horizontal member of the crank 23 fits between two forwardly extending arms of the vertical fork.

As shown the crank 23 is supported from 100 hangers 28 depending from a fixed frame member, bearings 29 being provided therein as shown in Fig. 3. An arm 30 of the crank 23 extends rearwardly from the crank and is hinged at the rear end to a lever or 105 vertical arm 31 connected to the vertically swinging member 32 of a knife switch. The member 32 is hinged as at 33 to a bracket 33^a and carries at its forward end a switch point which is adapted to be brought 110 into contact with a fixed fork 35 of the switch, thereby closing an electric circuit, the terminals of which are indicated by reference numerals 36 and 37. This circuit includes a pump illustrated diagrammatically 115 at 38 which may be located at any convenient point adjacent the pipe line which leads from the sump hole. Preferably the switch is provided with a covering 45 which protects it from the moisture.

The operation of the device will be evident. As the water rises the arm 16 is automatically raised by means of the float 20 thus pushing the rod 12 rearwardly and releasing the upper end of lever 8 whereby the suction within the pipe line automatically opens the valve 4 for pumping. The spring 13 is not of sufficient strength to prevent valve 4 being opened by suction when the lever 8 has been released by rais- 120 125 130

ing the float arm 20 but is merely sufficient to keep the valve 4 tightly closed when suction in the pipe line is released and serves to keep the pump primed for resumption of pumping at any time.

As the level of the water in the hole is lowered the float arm is automatically lowered by means of the weight 19, thereby drawing the upper end of lever 8 forwardly and the lower end rearwardly thus closing the valve 4. The weight 19 is sufficient to prevent suction from opening the valve and to keep the pump primed for resumption of pumping at any time.

While according to the preferred embodiment of the invention both the pump control switch 30 and the valve which controls the float 20 is of sufficient size to raise the weight 19 as the level of the water rises, it is evident that each may be separately controlled by the pump control switch which controls the operation of the pump 38 which keeps the water in the pump hole below a determined level.

As the level of the water rises the float 20 lifts the arm 16 and raises the lever 21, and member 22. The lower forwardly projecting arm of the vertical fork 26 carried by the member 22 bears against the horizontal arm of the crank 23 raising it to the horizontal position, after which the spring 25 operates to quickly throw the crank to its uppermost position at which it is arrested by the upper member of the vertical fork.

In Figs. 4, 6 and 8 there is shown a construction in which the parts designated by horizontal position, after which the spring 25 operates to quickly throw the crank to its uppermost position at which it is arrested by the upper member of the vertical fork. See Fig. 11. This movement of the crank 23 is transmitted through levers 30 and 31 to the knife switch 32, the point of which is forced between the rollers 34 and spring contact members of the fork 35; see Fig. 10.

Throwing the switch 34 closes a circuit which is not completely shown in the drawings but is indicated in Fig. 1 and includes the terminals 36, 37 and the pump 38 shown diagrammatically and preferably located within the sump hole. The pump, of course, communicates with the suction pipe which extends into the sump hole, or with an extension of said suction pipe.

When the water is lowered beyond a predetermined level the switch is again suddenly and automatically pulled to open the circuit, the operation being the reverse of that which takes place when the circuit is closed.

The rollers 34 in the connecting switch serve to prevent any arc as the switch is thrown or pulled.

The level to which the water rises may be regulated by adjusting the point of connection between the end of the lever 21 and the float arm 16.

The switch shown in Fig. 9 is designed for use with alternating current but operates upon the same principle as the one already described. For a three phase motor using alternating current three wires are necessary and three knife switches are provided, each being connected to an insulating rod or cylinder 40 which is journaled as 42. For dis-

rect current only the center connecting switch is used.

The vertical lever 31 operated by the arm 30 of the crank 23 is in this case connected to the center member only of the switch, 30.

As by throwing this member the other two will also be thrown. Where it is desired to use this switch for direct current the center switch only is used, the other members being

made detachable from the insulating member.

While according to the preferred embodiment of the invention both the pump control switch and the valve which controls the float 20 is of sufficient size to raise the weight 19 as the level of the water rises, it is evident that each may be separately controlled by the pump control switch which controls the operation of the pump 38 which keeps the water in the pump hole below a determined level.

As the level of the water rises the float 20 which rests upon the surface of the water, it is evident that other means, controlled by operation of the pump, may be employed.

In Figs. 4, 6 and 8 there is shown a construction in which the parts designated by horizontal position, after which the spring 25 operates to quickly throw the crank to its uppermost position at which it is arrested by the upper member of the vertical fork.

See Fig. 11. This movement of the crank 23 is transmitted through levers 30 and 31 to the knife switch 32, the point of which is forced between the rollers 34 and spring contact members of the fork 35; see Fig. 10.

Throwing the switch 34 closes a circuit which is not completely shown in the drawings but is indicated in Fig. 1 and includes the terminals 36, 37 and the pump 38 shown diagrammatically and preferably located within the sump hole. The pump, of course, communicates with the suction pipe which extends into the sump hole, or with an extension of said suction pipe.

When the water is lowered beyond a predetermined level the switch is again suddenly and automatically pulled to open the circuit, the operation being the reverse of that which takes place when the circuit is closed.

The rollers 34 in the connecting switch serve to prevent any arc as the switch is thrown or pulled.

The level to which the water rises may be regulated by adjusting the point of connection between the end of the lever 21 and the float arm 16.

The switch shown in Fig. 9 is designed for use with alternating current but operates upon the same principle as the one already described. For a three phase motor using alternating current three wires are necessary and three knife switches are provided, each being connected to an insulating rod or cylinder 40 which is journaled as 42. For dis-

rect current only the center connecting switch is used.

The vertical lever 31 operated by the arm 30 of the crank 23 is in this case connected to the center member only of the switch, 30.

As by throwing this member the other two will also be thrown. Where it is desired to use this switch for direct current the center switch only is used, the other members being

made detachable from the insulating member.

While according to the preferred embodiment of the invention both the pump control switch and the valve which controls the float 20 is of sufficient size to raise the weight 19 as the level of the water rises, it is evident that each may be separately controlled by the pump control switch which controls the operation of the pump 38 which keeps the water in the pump hole below a determined level.

As the level of the water rises the float 20 which rests upon the surface of the water, it is evident that other means, controlled by operation of the pump, may be employed.

In Figs. 4, 6 and 8 there is shown a construction in which the parts designated by horizontal position, after which the spring 25 operates to quickly throw the crank to its uppermost position at which it is arrested by the upper member of the vertical fork.

See Fig. 11. This movement of the crank 23 is transmitted through levers 30 and 31 to the knife switch 32, the point of which is forced between the rollers 34 and spring contact members of the fork 35; see Fig. 10.

Throwing the switch 34 closes a circuit which is not completely shown in the drawings but is indicated in Fig. 1 and includes the terminals 36, 37 and the pump 38 shown diagrammatically and preferably located within the sump hole. The pump, of course, communicates with the suction pipe which extends into the sump hole, or with an extension of said suction pipe.

When the water is lowered beyond a predetermined level the switch is again suddenly and automatically pulled to open the circuit, the operation being the reverse of that which takes place when the circuit is closed.

The rollers 34 in the connecting switch serve to prevent any arc as the switch is thrown or pulled.

The level to which the water rises may be regulated by adjusting the point of connection between the end of the lever 21 and the float arm 16.

The switch shown in Fig. 9 is designed for use with alternating current but operates upon the same principle as the one already described. For a three phase motor using alternating current three wires are necessary and three knife switches are provided, each being connected to an insulating rod or cylinder 40 which is journaled as 42. For dis-

rect current only the center connecting switch is used.

The vertical lever 31 operated by the arm 30 of the crank 23 is in this case connected to the center member only of the switch, 30.

As by throwing this member the other two will also be thrown. Where it is desired to use this switch for direct current the center switch only is used, the other members being

made detachable from the insulating member.

A communicates with the lower portion of a barrel or tank C, near the top of the barrel to which is connected a pipe D which discharges into the pan 43. When the barrel C is filled from the discharge of the pump the water running through the pipe D pulls the pan down, as described, throwing the switch and allowing water to flow through the end of the discharge pipe B, which keeps the pan down and the power off the pump A until the water ceases flowing.

The barrel C should be provided with a plurality of small holes in its side between the level at which the discharge pipe 15 of the pump is connected and the level at which the pipe D leaves the barrel. This arrangement allows the water to fall a few inches below the pipe D after the pump has ceased to operate and thus allows the pump 20 to continue to operate for a few moments after starting so that a free flow is insured before the discharge from the pipe D pulls the switch and stops the motor.

Any water which may be left in the barrel C 25 when the pump A stops, flows back through the pump discharge pipe, and keeps the pump always primed, ready to resume pumping at any time.

Near the end of the discharge pipe B of 30 the main pipe line a check valve E should be placed which prevents air coming back through the end of the discharge pipe while the pump is running. The end of the pipe B should be turned slightly upward which 35 will insure its always holding sufficient water on the check valve to keep the same tightly sealed against the admission of air.

For convenience the pump A, check valve E, barrel C, and the automatic cutoff switch 40 H should all be placed as near together as possible and near the end of the discharge pipe B.

To prevent the switch H, which is located on the outside of the mine from starting again as soon as the water ceases flowing and 45 before the sump holes 1 and 11 have again filled a second automatic switch K of the type shown and described in connection with Figs. 1 and 2 should be placed at the end 50 of a suction pipe in one of the water holes. Thus power will not be furnished to the pump until the water hole has again filled to the determined level as the electric power line runs directly to the automatic cutoff 55 switch outside the mine.

The auxiliary cutoff switch should be placed in the hole furnishing the most water, thus insuring that all the holes are dry when the power is cut off.

60 If all the pump holes furnish the same amount of water the check valve at the end of one suction pipe may be tightened by adjusting the coil spring 13 or by inserting a stronger spring which causes the valve to 65 admit water very slowly thus insuring that

the hole in which this valve is placed will be the last one to be pumped dry.

Each of the water holes must be furnished with the automatic check valve, but it is necessary to use the complete apparatus including the switch in one hole only.

Where the end of the discharge pipe B does not have sufficient pull to draw the water out of the mine after being started by the pump, it is not necessary to use any of 70 the apparatus described on the outside of the mine, as the pump must be run continuously as long as there remains any water to be pumped. In such case the pump is located within the mine together with an 75 automatic starting box which is used for starting a pump gradually in a known manner.

When the apparatus is properly installed, 80 it will be seen that water may be automatically pumped from a mine or place where water accumulates and as soon as the mine is dry the power is automatically cutoff. The services of pumpmen are thus completely replaced and a saving of many thousands of dollars per year in labor costs is effected.

While the device has been described with great particularity in order that a clear understanding of the operation of the device 95 may be had it will be evident that many of the details may be varied without departing from the spirit of the invention which is to be limited only by the appended claims.

What I claim is:

1. In a mine pumping device in combination a suction pipe having communication with a water hole, a check valve located within said pipe, a pump also communicating with said pipe and adapted to initiate the flow of water therein and common means operated in accordance with the amount of water in the hole for regulating the operation of the pump and said suction valve.

2. In a mine pumping device, in combination, a suction pipe having communication with a water hole, a check valve located within said pipe, a pump also communicating with said pipe and adapted to initiate the flow of water therein, and common means operated in accordance with the amount of water in the hole for regulating the operation of the pump and said suction valve, said means comprising an arm bearing a float adjacent one end thereof, connecting levers between the opposite end of said arm and said valve, a regulating switch for said pump, and connecting levers between said switch and said arm.

3. In a mine pumping device in combination, a suction pipe having communication with a water hole, a check valve located within said pipe and adapted to initiate the flow of water therein, and common means operated in accordance with the level of the

water in the hole for regulating the operation of the pump and said suction valve, said means comprising a float, and levers connecting said float with the suction valve 5 and a pump controlling switch respectively.

4. In a mine pumping device, in combination, a motor driven pump, a power circuit for controlling the pump, a knife switch located within the circuit, a suction pipe communicating with a water hole and having a check valve therein, and common means operated in accordance with the level of the water in the hole for operating said switch and said check valve.

15 5. In a mine pumping device, in combination, a suction pipe having communication with a water hole, a check valve located within said pipe, an electrically driven pump also communicating with said pipe 20 and adapted to initiate the flow of water therein, a power circuit for controlling the pump, a knife switch located within the circuit, a float operated in accordance with the level of the water in the mine, a float 25 arm connected thereto, a vertical lever con-

nected thereto having its upper portion forked and slotted, a crank arm journaled in fixed frame members and passing through said slotted forks, a vertical bracket secured to one of said forks and having forwardly 30 projecting portions which straddle said crank arm, said crank arm being connected with said switch, whereby raising or lowering said float arm beyond a certain level automatically operates said switch, and 35 other connections between the said float arm and the said check valve.

6. In a device of the character described, in combination, a suction pipe communicating with a water hole, a pump communicating with said suction pipe, a check valve located within one end of said pipe, a float arm operated in accordance with the level of the water within said hole, a pump controlling switch and adjustable means for 40 connecting said float arm with said check valve and said pump controlling switch respectively.

In testimony whereof I affix my signature
CHESTER LEWIS.
